UNITED STATES PATENT OFFICE.

EMIL J. MEISSNER, OF WEST HOBOKEN, NEW JERSEY.

DESIGN FOR A DINNER-PLATE.

58,039.

Specification for Design.

Patented May 31, 1921.

Application filed October 1, 1920. Serial No. 414,122. Term of patent 7 years.

To all whom it may concern:

Be it known that I, EMIL J. MEISSNER, a citizen of the United Staets of America, residing at West Hoboken, in the county of Hudson and State of New Jersey, have invented a new, original, and ornamental Design for Dinner-Plates, of which the following is a specification, reference being had to the accompanying drawing, forming part thereof.

Figure 1 is a plan view of a dinner plate showing my new design.

Fig. 2 is a longitudinal cross-section on the line 2—2 of Fig. 1.

Fig. 3 is a perspective view on a reduced scale.

Throughout the drawings like reference characters indicate like parts.

1 is the body of the plate; 2 a depression for a meat or other main element of the dinner menu; 3 a depression for the vegetables; 4 a depression for the bread; 5 a depression for the salad; 6 a depression for the butter; 7 a depression serving as a saucer for a coffee cup, and 8 a similar depression for receiving a cream jug. The oblong depression 9 is designed to receive a knife and fork.

I claim:

The ornamental design for a dinner plate as shown.

EMIL J. MEISSNER.
